His ATTORNEY

UNITED STATES PATENT OFFICE.

EDWARD CHAMBERLIN, OF CINCINNATI, OHIO, ASSIGNOR OF ONE-HALF TO
HORACE S. PEASE, OF CINCINNATI, OHIO.

ADJUSTABLE SHADE-BRACKET.

SPECIFICATION forming part of Letters Patent No. 696,390, dated March 25, 1902.

Application filed July 3, 1897. Serial No. 643,435. (No model.)

To all whom it may concern:

Be it known that I, EDWARD CHAMBERLIN, a citizen of the United States, residing at Cincinnati, in the county of Hamilton and State 5 of Ohio, have invented certain new and useful Improvements in Adjustable Brackets, of which the following is a specification.

My invention relates to novel means for adjusting shades and curtains without detaching or removing the bracket from the casing.

The object of my invention is to produce a simple, durable, and effective bracket adapted to be easily and quickly adjusted vertically or horizontally without removing the 15 wall-plate or base after it has been securely fastened to the window or other casing.

My invention consists in the parts and combination of parts shown in the drawings and hereinafter described, and pointed out in the 20 claims.

In the drawings, Figure 1 is a front elevation showing a pair of brackets supporting a window-shade roller. Fig. 2 is a side elevation of the right-hand bracket. Fig. 3 is a 25 similar view of the left-hand bracket. Fig. 4 is an enlarged front elevation of one of my brackets, showing one end of the window-shade roller supported therein, the dotted lines indicating the movable support and 30 roller in another position. Fig. 5 is a transverse section taken on the line $x-x$, Fig. 3, showing a side view of the screw-bolt looking in the direction of the arrow. Fig. 6 is a front view of a modified form of bracket, 35 showing a portion only of the movable support. Fig. 7 is a side view of the bracket, showing both a curtain-pole support and shade-roller applied thereto, the curtain-pole support being partly broken away for lack of 40 space. Fig. 8 is a transverse section on the line $y-y$, Fig. 7, showing a side view of the nut and bolt which secure the movable support to the base looking in the direction of the arrow.

45 These brackets are primarily intended for supporting window-shade rollers or curtain-poles, but may be used for any analogous purpose. It often happens that portions of the moldings or window-casings are formed with 50 rough or uneven surfaces, rendering it difficult to secure the ordinary bracket thereto.

Windows in different houses often vary considerably in width, and shade-rollers which would be the proper width in one house are frequently found to be either too narrow or 55 too wide for use in another house where the ordinary bracket is depended upon to support them. Again, windows in one house are often higher than those in another, and if the change is made from a short to a long window the 60 shade is too short and leaves a space at the bottom of the window which must be temporarily covered by splicing the shade to make it reach or it is rendered entirely useless for the new situation. I overcome all of these difficulties by means of my invention, by which 65 I am enabled to easily and quickly and without removing the bracket from the window adjust the shade or curtain up or down or sidewise several inches to the desired location.

I construct the base or wall-plate A of the bracket of suitable length to allow for vertical adjustment of the movable support thereon, said base having upon the outer or inner 75 edge two rows of notches to receive and retain the movable support B of the bracket, which is held in an adjusted position by means of a nut C and bolt D, the base having an elongated slot to permit the bolt to take and 80 be adjusted vertically therein. When the base is constructed in the form shown in Fig. 4, I provide a bead a upon each side of the slot to form a bearing for the nut C to take against, and if the elongated slot be larger 85 than the bolt-head a suitable washer E may be employed with the form of base shown in Figs. 6 and 7, and I prefer it at all times as a means for preserving the visible surface of the bracket from becoming scratched or roughened when tightening the bolt. In the form 90 of base showing the notches upon the visible surface a washer E is required to bear against arms b to hold them in the notches when the bolt is screwed up and sufficiently tightened. 95 This operation may be performed by means of a screw-driver. When the notches are upon the under side of the base, the nut C is preferably made long enough to extend across and take partly over and around the arms b of 100 the movable support, having suitable grooves formed upon one face thereof, as shown in

Fig. 7, to partly receive said arms. This construction enables me to dispense with the beads *a a* and also with the washer *E* and gives a smooth and finished appearance to the 5 visible portion of the base.

The movable supports *B* are preferably constructed of wire of any suitable size, so bent as to form an eye to receive the end of the shade-roller, with two arms of any desired 10 length at right angles thereto, adapted to be secured to the base above described and be adjusted to any desired position. After the base *A* has been screwed or otherwise secured to the window-frame and the movable support 15 attached thereto it may be adjusted up or down or sidewise by simply loosening the bolt sufficiently to allow the arms *a* to pass between the washer or nut and the projecting edges of the base, and for sidewise adjustment 20 a very slight loosening is necessary, and the arms may then be adjusted to the position shown in Fig. 5 or entirely removed and reversed to the position shown by the dotted lines in Fig. 4 or to any other position necessary 25 to accommodate the bracket to the length of roller or desired position of the shade or blind.

I prefer to make the notches in the bases in substantially the forms indicated in the drawings, so that they will be right and left hand bases instead of interchangeable, as this construction enables me to more firmly secure the movable supports to the base. It will be seen by reference to Figs. 2, 3, and 7 that each 30 notch in one row has a shoulder on its lower side, and each corresponding notch in the opposite row a similar shoulder on its upper side, whereby the arms of the movable support will each be furnished with a bearing 35 above and below. This construction prevents vertical shifting of the arms, as the lower shoulders of one rod form bearing-surfaces for the downward pressure, while the upper shoulders of the other row form bearing-surfaces for the upward pressure. When the 40 supports are fastened in position, vertical movement of the support is overcome and the same held rigidly in any desired position. As shown in the drawings, the side of each notch 45 opposite the bearing-shoulder is tapered off to facilitate adjustment and render the same more secure. By reversing the movable supports and placing them in position indicated by the dotted lines, Fig. 4, instead of the position 50 shown in Fig. 1, the notches will be hid from view.

The bearing or eye formed upon the movable support in Fig. 3 is made square-shaped to receive the left-hand end of the roller as 60 commonly constructed, so that the part which takes into it will not turn or rotate therein, while the one shown in Fig. 2 is made round to permit the journal of the opposite end of the roller to turn or rotate in the usual way.

65 A desirable feature of my bracket is its adaptability to support both the curtain-pole and the shade-roller at the same time. This

is done by providing each bracket-base with a movable curtain-pole support, as *B'*, and shade-roller support, as *B*, and placing the former above the latter upon the base. The movable curtain-pole support is made to extend out farther from the base than the shade-roller support, so that the shade will be free from contact with the curtain. By mounting 70 both the curtain-pole support and the shade-roller support upon the same base I am enabled to reduce the cost of construction, preserve the casing from additional marring due to screwing or nailing on two bases instead of one, and save labor in putting on and removing the brackets.

It will be seen that by means of my bracket the ends of the roller and pole may be adjusted and held at any desired point extending over a space of several inches sidewise either inside or outside of the base and extending over a space of several inches vertically without defacing the window-casing by unscrewing the base and changing its location thereon.

I am aware that others have heretofore constructed brackets adapted to be adjusted both vertically and horizontally without removing the base, and I do not, therefore, claim the 95 same broadly; but

What I do claim, and desire to secure by Letters Patent, is—

1. In an adjustable bracket, the combination of a fixed vertical base having a central vertical slot, a double row of notches upon its under face, an adjustable support having arms extending at right angles across said row of notches, a bolt taking through said slot and a nut, having grooves to receive the 100 arms of the support, engaging with said bolt to secure the parts together, substantially as set forth.

2. In an adjustable bracket the combination of a fixed vertical base having a longitudinal slot, a double row of notches upon one face of said base, an adjustable support having arms extending at right angles across said row of notches, a bolt taking through 110 said slot, and a nut engaging with the bolt 115 to secure the parts together, substantially as set forth.

3. In an adjustable bracket, the combination of a fixed vertical base having a central longitudinal slot and a double row of notches 120 upon one face thereof, two supports each having arms with free ends to take transversely across and engage with said notches, one of said supports being formed to retain a curtain-pole and the other a window-shade roller 125 and be adjusted vertically and laterally independent of the other to any desired position and a nut and bolt adapted to secure the parts together, substantially as set forth and for the purposes specified.

EDWARD CHAMBERLIN.
